UNITED STATES PATENT OFFICE.

ANNA SCANLAN, OF NEW YORK, N. Y.

MATTRESS.

1,381,751.

Specification of Letters Patent. Patented June 14, 1921.

Application filed May 12, 1920. Serial No. 380,755.

To all whom it may concern:

Be it known that I, ANNA SCANLAN, a citizen of the United States, and a resident of the city of New York, in the county and State of New York, have invented an Improvement in Mattresses, of which the following is a specification.

My invention relates to mattresses, more particularly mattresses extensively used in cases of sickness such as for example hospital mattresses, and aims to provide a mattress which will enable the attendant to give every attention without moving the patient.

In many cases of illness any movement of the patient may in a great measure endanger his life and since it is necessary at times to move the patient in order to permit proper functioning of certain organs it becomes extremely desirable to provide a suitable means whereby proper functioning may take place with a minimum of disturbance to the patient. It is an object of this invention to provide a mattress so arranged that the excretionary organs may function properly with practically no movement of the patient, and this object is accomplished in that the invention provides a mattress suitably recessed whereby the excretionary receptacle may be readily and easily placed and removed without any disturbance of the patient.

In the accompanying drawings an illustrative embodiment of my invention is presented.

35 Figure 1 is a perspective view showing the closures in place in the recessed portion.

Fig. 2 is a perspective view showing the closures removed and the excretionary receptacle in position.

40 In Fig. 2 the mattress 1, tufted in the usual manner, is recessed at 2. The recess is situated at the transverse median of the mattress, extends to substantially equal distances on either side of said median, and from one side 45 in a transverse direction to a point beyond the longitudinal median; as, for example, a distance of from about two-thirds to three-fourths of the width of the mattress. The recess should be so dimensioned as to depth 50 that an excretionary receptacle such as, for example a bed pan 3 ordinarily used in cases of sickness may be readily accommodated. While the recess may be of any suitable depth it will be realized that the upper surface of 55 the excretionary receptacle should be practically flush with the top of the mattress.

In order to maintain the mattress in a clean and sanitary condition the greater part of said mattress may be covered by an impervious medium, such as a rubber blanket 6, 60 which is cut and arranged to fit into the recess thus thoroughly protecting the mattress and recessed portion and in consequence of the fitting into the recess, probable disarrangement of the impervious medium is 65 lessened.

Fig. 1 shows the mattress 1 with the recessed portion 2 closed. The closing of said recessed portion 2 may be by any suitable closure, such as, for example, a tufted article 70 similar to the mattress itself, and this closure may consist of a single member or a plurality of members. It has been found very satisfactory to make such closure in two parts, one of which is covered and tufted in the usual 75 manner, the other portion being made in the ordinary way but in addition having thereon an impervious medium which completely covers the same. When such closure, or closures, are in proper position and the bed 80 made up, the mattress has every appearance of an ordinary mattress and such would be the normal condition, the closures being removed only at such times as it may be found necessary in the attendance upon the patient. 85

In order to permit proper functioning without disturbing the patient all that is required in connection with the invention is that the closure or closures be removed from the recess 2 and the excretionary receptacle 90 placed therein. In the event that the closure is composed of two members 4 and 5 the bed pan, or other excretionary receptacle, is inserted to the position previously occupied by closure member 4, and the remaining portion of the recess is closed by closure member 5. The closure member 4 and the excretionary receptacle 3 may be so proportioned that the space occupied by them is substantially 95 the same. To remove the receptacle the closure 5 is first removed, and the receptacle then withdrawn. After removal of the receptacle the recess is at once closed by the replacement of closures 4 and 5.

It is apparent that throughout the whole 105 attendance there has arisen no necessity to disturb the patient and, as has been pointed out, this feature is of the greatest value since endangering the life of the patient is thereby avoided.

The invention therefore provides a mattress which permits proper functioning of

the excretionary organs, lessens the labors of the attendants, and obviates endangering the life of the patient in cases of severe illness where even a slight movement would be most detrimental. Furthermore, the mattress provides a most convenient manner of giving attendance in all cases of sickness and is adapted to home use as well as in hospitals since by closing the recessed portion by means of suitable closures the mattress has every appearance and comfort of a mattress of the usual kind.

In the event that it is necessary to allow the excretionary receptacle to remain in place at all times as in the case of an incontinent patient an inflated ring comprised of impervious material may be placed upon the receptacle upon which the patient rests, said ring adding greatly to the comfort of the patient and preventing further ailment, such as for example, bed-sores.

In addition to the advantages set forth above, more particularly the use of the mattress with incontinent patients, the mattress is also well adapted for use in surgical cases

such as, fractures, cases involving members inclosed in plaster casts, etc. Furthermore, by a simple reversal of the mattress an un-recessed surface is presented whereby the bed becomes of the usual type and admits of freshening in a very simple manner.

I claim:

In combination with a mattress having a recess, said recess being at said mattress's transverse median and extending to substantially equal distances on each side thereof, and extending transversely from one side of said mattress to a point beyond the longitudinal median and said recess having a depth substantially one-half the depth of said mattress and having perpendicular walls, a plurality of closures for said recess, one of said closures being covered with an impervious medium and an impervious medium adapted to fit into said recess and to cover substantially the whole of said mattress.

In testimony whereof, I have signed my name to this specification this 8th day of May, 1920.

ANNA SCANLAN
